UNITED STATES PATENT OFFICE.

THURE E. DAHL, OF NEW YORK, N. Y.

DESIGN FOR A HOLDER FOR LIGHTING FIXTURES.

Application filed July 21, 1921. Serial No. 486,578. Term of patent 3½ years.

To all whom it may concern:

Be it known that I, THURE E. DAHL, a subject of the King of Sweden, and resident of New York, in the county of New York and State of New York, have invented a certain new, original, and ornamental Design for a Holder for Lighting Fixtures, of which the following is a specification, reference being had to the accompanying drawing, forming part thereof. The figure is a perspective view of a holder for lighting fixtures showing my new design. I claim: The ornamental design for a holder for lighting fixtures, as shown.

THURE E. DAHL.
